UNITED STATES PATENT OFFICE.

ANTON F. HAUMERSON, OF FORT ATKINSON, WISCONSIN, ASSIGNOR TO POUNDER HARROW COMPANY, OF FORT ATKINSON, WISCONSIN.

COMBINED MERRY-GO-ROUND AND TEETER BOARD.

1,421,468.

Specification of Letters Patent.

Patented July 4, 1922.

Application filed July 23, 1921. Serial No. 487,018.

To all whom it may concern:

Be it known that I, ANTON F. HAUMERSON, a citizen of the United States of America, residing at Fort Atkinson, in the county 5 of Jefferson and State of Wisconsin, have invented certain new and useful Improvements in Combined Merry-Go-Rounds and Teeter Boards, of which the following is a specification.

10 This invention relates to certain new and useful improvements in combined merry-go-rounds and teeter boards particularly useful for the pleasure of children in public playgrounds or private play yards.

15 The object of the invention is to generally simplify and improve the construction of teeter boards and supports therefor whereby a durable construction will be presented and friction reduced to a minimum; to mount 20 the teeter board for rotation about a vertical axis whereby the device may be employed as a merry-go-round; and to provide for the simple erection of the device so as to properly maintain its position when in use and to 25 permit ready removal as a unit to a different place of use if desired.

Another object is to provide a simplified 30 and cheap construction of combined merry-go-round and teeter board which will embody durability and efficiency in operation.

With the above general objects in view and others that will appear as the nature of the invention is better understood, the same 35 consists of the novel form, combination and arrangement of parts hereinafter more fully described, shown in the accompanying drawing and claimed.

In the drawing, wherein like reference 40 characters designate corresponding parts throughout the several views,

Figure 1 is a view partly in side elevation, partly broken away and partly in vertical section of a combined merry-go-round and teeter board constructed in accordance with 45 the present invention.

Figure 2 is a top plan view of the device shown in Fig. 1.

Figure 3 is a vertical transverse sectional view taken to one side of the teeter board 50 support,

Figure 4 is a horizontal sectional view taken upon line IV—IV of Fig. 1,

Figure 5 is a perspective view of a modi-

fied form of supporting means for the standard, and

Figure 6 is a fragmentary elevational view showing a modified form of roller carrying frame.

Referring more in detail to the several views, the invention embodies an upright 60 standard 5 preferably cylindrical in form and turned from a stout piece of oak wood, a suitable spider casting 6 being rigidly fastened against the lower end of the standard 5 with its arms projecting radially in 65 a horizontal position, and a plurality of legs 7 being fastened to the central portion of the standard 5 and thence extending downwardly and outwardly to vertical lower portions which extend through openings in the outer 70 ends of the spider arms for bracing said legs in their proper relation. The lower ends of the legs 7 are sharpened so as to readily penetrate the ground whereby the standard 5 is efficiently supported against 75 lateral displacement and at the desired elevation.

A rectangular frame 8 is mounted upon the upper end of the standard 5 in a vertical position and the same has a horizontal roller 80 9 journaled therein between the top and bottom bars of the same for supporting a teeter board 10 which projects through said frame 8. The board 10 is provided with a series of transverse grooves 11 of arcuate 85 form for selective reception of the upper portion of the roller 9 so as to permit proper balancing of the board at opposite sides of the roller in accordance with the variation of weight upon the ends of said board when 90 in use, the interfitting relationship between the board and the roller by the provision of these grooves preventing accidental longitudinal displacement of the board 10 to a large degree while permitting easy rocking 95 of said board.

In order to permit the board 10 to revolve relative to the standard 5 so as to permit use of the device as a merry-go-round, a ring 12 is fitted onto the upper end of the standard 100 5 and is provided with an outwardly projecting pivot pin 13 which pivotally extends through an opening in the bottom frame bar of the frame 8. A cotter pin 14 may be employed for maintaining the frame 8 on the pivot 13 while allowing the frame 8 and

the parts carried thereby to freely swivel about a vertical axis and thus permitting the persons seated upon the board 10 to enjoy the pleasures of a merry-go-round or a teeter board at will.

Referring to Fig. 5, wherein a modified form of supporting means for the standard 5 is shown, said supporting means comprises a one piece casing including a socket portion 20 into which the lower end of the standard 5 may be seated and there secured by any suitable form of securing device such as screws or nails adapted to pass through the apertures 21 and into the standard 5. Integral with the bottom of the socket member 20 are a plurality of radially extending arms 22 suitably reinforced and provided with depending legs 23 at their outer ends, said legs being pointed to penetrate the ground as described with respect to the legs 7.

Referring to Fig. 6, the substantially rectangular frame 8' may be opened at its top of the substantially U-shape with the roller 9' journaled horizontally therein and adapted to be pivoted to the standard 5 by means of the pin 13. This form of frame will allow the board 10 to be more readily placed upon the roller 9' and the danger of children having their hands caught under cross pieces of the rectangular frame shown in Figs. 1 and 3 is eliminated. However, to all intents and purposes, the substantially rectangular open frame 8 is equivalent to that indicated by 8' in Fig. 6. Otherwise the structure is similar to Fig. 1.

While there is herein shown and described the preferred embodiment of the present invention, it is nevertheless to be understood that minor changes may be made therein without departing from the spirit and scope thereof.

What is claimed as new is:

1. A combined merry-go-round and teeter board comprising a support, a frame supported in a vertical position upon the upper end of said support and swiveled upon the latter about a vertical axis, a transverse member supported by said frame, a teeter board extending through the frame and resting upon said transverse board, said transverse member comprising a horizontal roller, and said board being provided with transverse grooves near its central portion for selective reception of said roller.

2. In a device of the class described, a standard having an open frame mounted in a vertical position upon the upper end thereof, a roller journaled transversely of the frame upon a horizontal axis, and a board extending through the frame and resting upon said roller for tilting movements.

3. In a device of the class described, a

standard having an open frame mounted in a vertical position upon the upper end 65 thereof, a roller journaled transversely of the frame upon a horizontal axis, and a board extending through the frame and resting upon said roller for tilting movements, said board being provided with a 70 series of transverse grooves in the central portion thereof for reception of the upper portion of said roller whereby said board is maintained against accidental longitudinal displacement while permitted to tilt. 75

4. In a device of the class described, a vertical standard having a relatively long board mounted thereon and movable relative thereto, a spider fixed to the lower end of said standard with radial horizontally 80 positioned arms, and angular legs anchored at their upper ends to the standard and extending outwardly and downwardly through the outer ends of the spider arms below said standard, the lower end portions of 85 said legs being pointed for penetrating the ground.

5. In combination with an upright standard having an axially projecting rigid pivot pin upon its upper end, a rectangular 90 open frame disposed in a vertical position upon the upper end of the standard and having said pins swiveled in the lower bar thereof whereby rotating of the frame is 95 permitted about a vertical axis, means supported by the frame for accommodating persons for travel about said standard, said last named means embodying a teeter board tiltable in the frame and adjustable longitudinally through the latter, and means to 100 prevent accidental longitudinal displacement of the board through the frame.

6. In combination with an upright standard having an axially projecting rigid pivot pin upon its upper end, a rectangular 105 open frame disposed in a vertical position upon the upper end of the standard and having said pins swiveled in the lower bar thereof whereby rotating of the frame is 110 permitted about a vertical axis, means supported by the frame for accommodating persons for travel about said standard, said last named means embodying a teeter board tiltable in the frame and adjustable longitudinally through the latter, and means to 115 prevent accidental longitudinal displacement of the board through the frame, said last named means including a transverse member within the frame, said board being provided with transverse grooves for 120 selective reception of said transverse member.

In testimony whereof I affix my signature.

ANTON F. HAUMERSON.
